UNITED STATES PATENT OFFICE.

DAVID C. WHEELER, OF BRIDGEPORT, CONNECTICUT, ASSIGNOR TO THE
ACME SHEAR COMPANY, OF SAME PLACE.

DESIGN FOR A MEMBER FOR PAIRS OF SHEARS.

SPECIFICATION forming part of Design No. 33,776, dated December 25, 1900.

Application filed November 6, 1900. Serial No. 35,677. Term of patent 14 years.

To all whom it may concern:

Be it known that I, DAVID C. WHEELER, a citizen of the United States, residing at Bridgeport, county of Fairfield, State of Connecticut, have invented and produced a new and original Design for a Member of a Pair of Shears, of which the following is a specification, reference being had to the accompanying drawing, forming part thereof.

10 The drawing is an elevation of my novel member of a pair of shears.

The leading or material feature of my design consists of a bow of the shape substantially as shown in the drawing and including 15 as a part of said bow a substantially straight inner side, as at A, a convex curved outer

side, as at B, and an elongated finger-opening C, whose outer side is a concave curve, as at D, and whose inner side is a convex curve, as at E. At the lower end of the bow 20 is an outwardly-curved arm F.

Having thus described my invention, what I claim as new, and desire to secure by Letters Patent, is—

The design for a member of a pair of shears, 25 substantially as herein shown and described.

In testimony whereof I affix my signature in presence of two witnesses.

DAVID C. WHEELER.

Witnesses:

A. M. WOOSTER,
S. W. ATHERTON.
